UNITED STATES PATENT OFFICE.

FREDERICK C. STIMMEL, OF CHATTANOOGA, TENNESSEE, ASSIGNOR TO THE CASEY-HEDGES CO., A CORPORATION OF TENNESSEE.

MUD RING FOR BOILERS AND METHOD OF APPLYING SAME.

1,416,762.

Specification of Letters Patent. Patented May 23, 1922.

Application filed May 23, 1921. Serial No. 471,571.

To all whom it may concern:

Be it known that I, FREDERICK C. STIMMEL, a citizen of the United States, residing at Chattanooga, in the county of Hamilton and State of Tennessee, have invented certain new and useful Improvements in Mud Rings for Boilers and Methods of Applying Same, of which the following is a full, clear, and exact specification.

10 This invention relates to steam boilers and particularly to the formation and attachment of mud rings thereto.

The present improvements may be used on various kinds of boilers, but are especially applicable to the type of boiler known as drop water firebox boiler which is used for supplying steam for drilling oil wells. The mud ring generally used in this type of boiler is made in the shape of a U, and the riveting 20 thereof to the firebox sheet and to the bottom of the boiler is very difficult and tedious, it being necessary to drive rivets with an air gun or by hand while they are held on through the small hand holes in the front 25 and bottom and on the throat sheet at the bottom. It has also been found that the rivets thus driven are not tight and often have to be caulked or redriven.

It is the object of the present invention to 30 provide an improved construction of mud ring which is so made that its rivets may be driven by a hydraulic riveting machine, thus insuring tightness in the setting thereof, and avoiding leakage, so that it is unnecessary 35 to caulk or redrive said rivets as in the prior form of mud ring mentioned. The construction and method of applying said improved mud ring will be first hereinafter described in connection with the accompanying 40 drawings, which constitute part of this specification, and then more specifically defined in the claims at the end of the description.

In the accompanying drawings, wherein 45 similar reference characters are used to designate corresponding parts throughout the several views:

Figure 1 is a longitudinal sectional view of the end portion of a boiler containing the 50 firebox and showing an intermediate step in the method of attaching the mud ring.

Figure 2 is a similar view showing the

mud ring completely formed and attached to the boiler, and

Figure 3 is a transverse section of the 55 structure shown in Figure 2.

In the drawings, 1 designates a boiler casing of the type hereinbefore mentioned, and 2 indicates the firebox. The mud ring is made in two parts. The lower part 3 has 60 its outer edge fastened to the boiler casing 1 by rivets 4, while the outer edge of the upper part 6 is fastened to the firebox 2 by rivets 7. The inner edges of said parts 3 and 6 of the mud ring are flanged upwardly and 65 downwardly at 5 and 8, respectively, said flanges being in vertical alignment with each other and adapted to be united to form the inner vertical wall 16 of the mud ring 18.

The section 6 of the mud ring is attached 70 to the firebox before the latter is inserted into the boiler casing 1, the rivets 7 being readily driven on a hydraulic riveting machine. After the firebox, with said section 6 of the mud ring attached thereto, has been 75 placed in the boiler casing, it may be raised therein, as shown in Figure 1, to permit the rivets 4, for fastening the section 3 of the mud ring to the boiler casing 1, to be driven on a hydraulic riveting machine 11, the ram 80 10 thereof extending between the flanges 5 and 8 of the mud ring sections. When all of the rivets 4 have thus been driven, the firebox 2 is lowered into proper position with the flange 8 of the upper section 6 of the 85 mud ring resting upon the edge of the flange 5 on the lower section 3 of said mud ring, and the abutting edges of said flanges then united by electric welding, as indicated at 12 in Figures 2 and 3, thus completing the 90 mud ring 18 and providing the same with a continuous unitary inner wall 16.

The fire door 17 may also be formed by electrically welding together the edges of flanges 13 and 14 on the boiler casing 1 and 95 firebox 2, respectively, the welded joint being indicated at 15 in Figure 2.

I claim:

1. A mud ring made in two sections for independent attachment, respectively, to the 100 firebox and casing of a boiler, said sections having vertical flanges to be subsequently connected together for completing said mud ring.

- 2
2. A mud ring made in two sections for independent attachment, respectively, to the firebox and casing of a boiler, said sections having vertical flanges to be arranged in alignment one above the other for having their edges subsequently united to complete said mud ring.
  3. The method of applying a mud ring to a boiler, which consists in forming said mud ring in two sections, independently attaching said sections, respectively, to the firebox and casing of a boiler, and finally uniting said sections.
  4. The method of applying a mud ring to a boiler which consists in forming said mud ring in two sections, independently attaching said sections, respectively, to the firebox and casing of a boiler, and finally welding said sections together.
  5. The method of applying a mud ring to a boiler which consists in forming said mud
- ring in two sections, attaching one section to the firebox of a boiler before it is placed in the casing of said boiler, attaching the other section of the mud ring to the boiler 25 casing after said firebox has been inserted therein, and finally uniting said sections.
6. The method of applying a mud ring to a boiler which consists in forming said mud ring in two sections having vertical inner 30 flanges, attaching one section of said mud ring to the firebox of a boiler before it is inserted into the casing of said boiler, attaching the other section of the mud ring to the casing of the boiler after the firebox has 35 been inserted therein, and finally uniting the edges of the flanges on said sections to form a continuous vertical wall around the inside of said mud ring.

In testimony whereof I have signed my 40 name to this specification.

FREDERICK C. STIMMEL.
